AXIAL FLOW COMPRESSOR

Jan Jerie, 27 Komornicka, and Miroslav Vlasák, 11 Na
Krufnici, both of Prague 6, Czechoslovakia
Filed Dec. 4, 1962, Ser. No. 242,287
Claims priority, application Czechoslovakia Dec. 15, 1961
2 Claims. (Cl. 230—122)

The invention relates to axial flow compressors, and more particularly to an axial flow compressor of improved efficiency, lower peripheral speed and reduced dimensions for equal compression per stage and flow rate as compared to conventional compressors.

The term compressor as employed in this specification and the appended claims will be understood to include blowers, fans, and like devices having alternating rows or stages of rotary and stationary blades, and means for actuating rotation of the rotary blades whereby movement or flow of a fluid substantially parallel to the axis of rotation is generated.

Axial compressors are commonly employed in gas turbines, and find a wide field of application in the chemical processing and other industries. Axial compressors have generally higher efficiency, lower weight, and smaller overall dimensions than centrifugal compressors of comparable capacity.

The kinetic energy spent in actuating rotation of the compressor rotor is stored in the flowing gas as it is being compressed. During compression, the gas particles flow along substantially cylindrical surfaces. The flow path of the gas particles along these surfaces is determined by the shape and arrangement of the blades.

It is customary to arrange the blades of an axial compressor in such a manner that the blade reaction is approximately 50 percent. The flow coefficient φ which expresses the ratio of the axial flow velocity w_a of the compressed gas to the peripheral velocity u of the blades has an approximate value of 0.5 in such an arrangement. The blades of an axial compressor have also previously been arranged for a higher reaction, even exceeding 100 percent, and the efficiency of the compressor may be raised to a limited extent by a higher reaction percentage.

The object of this invention is an improvement in the efficiency of the known axial flow compressors and/or reduction of power input, compressor size and rotor speed as compared to known axial flow compressors of comparable capacity substantially beyond the improvement available by adjustment of the blade reaction.

Other objects and many of the attendant advantages of this invention will be readily appreciated as the same becomes better understood as the disclosure proceeds.

For a better understanding of this invention, the attached drawing illustrates operational characteristics and structural features of known axial flow compressors as well as corresponding characteristics and features of a compressor according to the instant invention.

The several portions of FIG. 1 relate to a conventional compressor having a blade reaction of 50 percent, FIG. 1a being a diagram of velocity relations, FIG. 1b being a fragmentary radial view of the blades of the compressor, and FIG. 1c being a fragmentary developed diagram of the cylindrical surface in which a gas particle moves.

The several portions of FIG. 2 relate to a conventional compressor having a blade reaction of 100 percent. FIGS. 2a, 2b, and 2c respectively illustrate velocity relations, the structural arrangement of the blades, and the flow path of a gas particle in such a compressor in a manner analogous to FIGS. 1a, 1b, and 1c.

FIG. 3 relates to a compressor of the invention, and the constituent parts of FIG. 3, namely, FIGS. 3a, 3b, 3c, correspond to the parts of FIGS. 1 and 2 identified by the same suffixes.

2

Referring initially to FIG. 1a there is seen the vector diagram correlating the peripheral speed u of the rotor blades in a compressor stage with the velocities of the gas particles. The vectors w_1 and w_2 represent the velocities of the gas relative to the rotor resulting from the vectorial combination of the absolute air stream velocities w_3 and w_4 with the rotor velocity u . The deviation of the velocities w_1 to w_4 from an axial velocity w_a are indicated by angles α_1 to α_4 respectively.

FIG. 1b shows two rotor blades R and two stator blades S in two axially successive rows of compressor blades separated by a clearance space m in the axial direction indicated by the arrow A. The blades are airfoils as is customary. The rotor blades R move relative to the stator blades S in the direction of the arrow u during operation of the compressor. It will be appreciated that FIG. 1b merely shows a small fragment of a conventional compressor in which the blades S are mounted fixedly in a housing of substantially circular cross section, and the blades R are mounted on a corresponding rotor body connected by a shaft to a source of driving power for rotation in the housing. The number of alternating rows of rotor and stator blades may be selected at will as is well known, and each circular row of blades includes a plurality of blades circumferentially spaced from each other in the manner evident from FIG. 1b.

The path of a gas particle in a substantially cylindrical surface about the compressor axis is illustrated in FIG. 1c in a developed view of the surface which intersects stator blade rows S_0 , S_1 and rotor blade rows R_1 and R_2 . The blades S_0 constitute the intake stator blades of a cascade, the blades R_1 and S_1 jointly constitute the first compressor stage, and the blades R_2 together with stator blades S_2 not shown in FIG. 1c constitute a second compressor stage. The path of a gas particle relative to the moving rotor is indicated by the broken line d_{12} , and its path relative to the stationary elements of the compressor by the fully drawn line d_{34} . The lines d_{12} and d_{34} diverge in the axial flow direction.

Under the conditions of 50 percent blade reaction illustrated in FIG. 1, the path d_{34} of each gas particle deviates substantially from the direction of the rotor axis. The inclination of the several portions of the path varies between limits defined by the angles α_3 and α_4 in FIG. 1a. Relative to the stationary compressor parts, the gas particles flow in a generally helical path about the compressor axis. The path deviates laterally from a true helix by undulations where the gas particles are deflected by the rotor and stator blades. The path d_{12} of each individual gas particle relative to the moving rotor also constitutes a helix but of opposite lead angle varying between extreme values represented by the angles α_1 and α_2 in FIG. 1a. In the compressor having a blade reaction of 50 percent to which FIG. 1 relates, the lead angles or inclinations of paths d_{12} and d_{34} are opposite and equal in magnitude on the substantially cylindrical surface considered.

FIG. 2 illustrates features and characteristics of an axial flow compressor differing from the compressor of FIG. 1 only by its blades R' and S' which are arranged for 100 percent reaction. The helical path of each gas particle relative to the stator of the compressor is represented in FIG. 2c by the solid line d_{34}' which may be termed a helix having a lead angle of 90° with such deviations as are inherent in the interaction between the gas particles and the blades S_0' , R_1' , S_1' , R_2' , etc. The inclination of the line d_{34}' relative to a line parallel to the rotor axis may vary between the angles α_3' and α_4' in FIG. 2a which are respectively defined by the vectors w_3' , w_4' and w_a in a manner evident from the preceding description of FIG. 1. The path d_{12}' of the gas particles relative to the rotor of the compressors to which FIG. 2

relates is inclined relative to an axial line by an angle which varies between the values α_1' and α_2' defined in FIG. 2a by the vectors w_1' , w_2' and w_a . The path of each gas particle relative to the rotor is thus much longer than in the compressor of FIG. 1 and the path relative to the stator is shorter. The smaller the lead angle, the longer the flow path, and the greater the energy losses.

It is evident from the preceding discussion of FIGS. 1 and 2, that an attempt at lowering energy losses in a compressor by shortening the path of the flowing fluid relative to the stator necessarily causes a lengthening of the path relative to the rotor. Only an insignificant gain in efficiency is thus available by adjustment of the blade reaction.

We have found that it is possible to modify the basically known structure of an axial flow compressor in such a manner that the lengths of the flow paths relative to the stator and to the rotor are simultaneously shortened. The relevant features and characteristics of a compressor of the invention are illustrated in FIG. 3 in which elements designated by double primed reference characters correspond to elements indicated by unprimed reference characters in FIG. 1 and by primed reference characters in FIG. 2.

One factor important for simultaneously shortening the flow paths of the gas particles in the compressor of our invention resides in control of the direction of gas flow in each space m between axially successive rows of rotor and stator blades. It will be assumed for the purpose of the disclosure that these spaces are uniform between the several rows, but the assumption is not relevant to this invention. The direction of flow in each space m must not be inclined more than 45° with respect to a corresponding axial plane.

In an otherwise conventional compressor, such an arrangement would result in excessive shortening of the blade length. Shortening of the path along the blades would be achieved in such a manner, and the friction losses due to relative movement of the flowing medium and the blade surfaces would be decreased. Losses due to secondary effects of the blade shortening, however, would practically balance any gain in efficiency which might be achieved by merely controlling the flow path in the space m . Two additional conditions must be simultaneously met.

A second necessary condition for improved efficiency in the axial flow compressor of our invention is proper relationship between the compressor dimensions which permits the compressor to be operated in such a manner that the conditions of the following Equation I are met:

$$\frac{D''^3 n}{V} \leq 50 \quad (I)$$

In this equation, D'' is the effective rotor diameter in meters as measured between the radially outermost tips of diametrically opposite rotor blades, n is the rotor speed in revolutions per minute, and V is the flow volume in cubic meters per second. The product of the cube of the effective compressor diameter in meters and of the rotary speed in reciprocal minutes should not be more than fifty times greater than the flow volume in cubic meters per second.

When the conditions of the above equation are met, the blades have a reasonable length, and the secondary losses are held to reasonably low values. Fully to achieve the objects of this invention, we have found it necessary to meet a third condition. The stator blades and the rotor blades must be airfoils having a maximum thickness of not more than twelve percent of the length of the chord.

When the above three conditions are met, it is possible to substantially reduce the overall dimensions of an axial flow compressor as compared to the dimensions of a conventional compressor of equal capacity. The efficiency of the apparatus is increased. The peripheral speed of

the rotor blades necessary for a predetermined compression ratio in a stage is lower in our compressor than in a conventional compressor of equal compression ratio. The energy input for a given compression effect is lower with a corresponding decrease in operating cost. The smaller compressor of our invention is inherently lower in first cost than a compressor of customary design, and occupies less space. It is driven by a smaller, and less bulky motor under otherwise comparable conditions.

Certain important features of our invention will be best understood by reference to the several portions of FIG. 3. FIG. 3a shows the vector diagram correlating the peripheral speed u of the rotor blades R'' in a compressor stage with the velocities of the gas particles in a manner analogous to FIG. 1a. FIG. 3b shows rotor blades R'' and stator blades S'' of axially successive rows separated by a space m , and FIG. 3c is a developed view of the cylindrical plane in which a gas particle travels through two compressor stages respectively represented by co-operating rotor and stator blades R_1, S_1 and R_2, S_2 . The paths of the particles relative to the rotor and to the stator are respectively indicated by lines d_{12}'' and d_{34}'' .

FIG. 3b also shows the angle β_2 defined by a tangent drawn on the mean line of the airfoil constituting a rotor blade at the trailing edge thereof, and by a line parallel to the axis drawn through the point of intersection of the tangent with the trailing edge. This angle β_2 will hereinafter be referred to as the outlet angle of the airfoil. We have found that the outlet angle of each airfoil constituting a rotor blade should not exceed 40° , and does not exceed 40° if the afore-mentioned three conditions are met.

The flow paths of the gas particles relative to the rotor and stator of our compressor are very short as compared to otherwise similar conventional axial flow compressors. The losses resulting from frictional contact between the gas particles and the airfoil surfaces are correspondingly reduced. It is evident from FIG. 3a that the peripheral rotor velocity u necessary to produce a given rate w_a of axial flow is low. High flow rates can thus be achieved with a compressor of relatively small effective rotor diameter, and at relatively low rotary speed. Since the flow coefficient φ is high, the energy transmitted to the flowing fluid by the rotor is great even at relatively low peripheral rotor speed, and the compression ratio obtained in each stage is high, and higher than available in otherwise comparable compressors of usual design.

The vector diagram of FIG. 3a, of course, is merely typical of a compressor of this invention, and modifications of the compressor represented by modified diagrams will readily suggest themselves to those skilled in the art. The compression ratio in each stage may be altered and the shape of the characteristic lines d_{12}'' and d_{34}'' may be correspondingly changed by varying the percentage reaction of the blades.

Whatever secondary changes may be introduced, it is essential that the three principal features of the invention enumerated above be adhered to, namely:

(1) The direction of flow in the space axially interposed between successive rows of stator and rotor blades should not be inclined by an angle of more than 45° to the direction of the rotor axis;

(2) The conditions of Equation I must be met; and

(3) The airfoils constituting the rotor blades must not have a thickness greater than 12 percent of the chord length.

Within these limitations, many modifications and variations of the present invention are possible in the light of the above teachings. It is therefore to be understood that within the scope of the appended claims, the invention may be practiced otherwise than as specifically described.

What we claim is:

1. An axial flow compressor comprising, in combination:
  - (a) stator means having an axis;
  - (b) rotor means rotatable about said axis;
  - (c) said stator means and rotor means each including a plurality of airfoil blades arranged in axially alternating rows on said stator means and on said rotor means for guiding a stream of gas in an axially extending path, the spacing of the radially outermost portions of diametrically opposite blades on said rotor means defining the effective diameter of said rotor means;
  - (d) each row of said airfoil blades on said rotor means defining with two axially adjacent rows of said airfoil blades on said stator means respective spaces therebetween, said path having respective portions in said spaces, each of said portions being inclined relative to said axis at an angle not greater than 45 degrees;
  - (e) the thickness of each of said airfoil blades being not greater than twelve percent of the chord length thereof; and
  - (f) actuating means for actuating rotation of said rotor

5

10

15

20

means about said axis at a speed sufficient to cause flow of said gas in said stream at a predetermined rate, the product of the cube of said effective diameter in meters times said speed in revolutions per minute not being greater than fifty times said rate in cubic meters per second.

2. A compressor as set forth in claim 1, wherein each airfoil blade has a profile mean line and a trailing edge, said mean line intersecting said trailing edge in a point, a tangent drawn on said mean line at said point and a line drawn parallel to said axis through said point defining an output angle not greater than 40 degrees.
